UNITED STATES PATENT OFFICE.

CÆSAR NEUMANN, OF NEW YORK, N. Y.

IMPROVEMENT IN HOOP-SKIRTS.

Specification forming part of Letters Patent No. 40,355, dated October 20, 1863.

To all whom it may concern:

Be it known that I, CÆSAR NEUMANN, of the city, county, and State of New York, have invented a new and useful Improvement in Hoop-Skirts; and I do hereby declare that the following is a full, clear, and exact description of the same, reference being had to the accompanying drawings, forming a part of this specification, in which—

Figure 1 represents a side elevation of my invention. Fig. 2 is a plan or top view of the same.

Similar letters of reference in both views indicate corresponding parts.

The object of this invention is to make the waist-band and the bustle rings of a hoop-skirt self-adjustable, according to the varying thickness of the body of the wearer. In order to effect this purpose, it is not sufficient to make the waist-band alone self-adjusting, because by increasing the length of the same the rotation of its different parts toward the adjoining ring is changed, and unless the length of the ring is increased in a corresponding ratio a strain is exerted on the tapes connecting said ring with the waist-band, and said tapes are liable to tear off in a short time. This difficulty is avoided and the object of the invention fully attained by making both the waist-band and the bustle-rings self-adjusting in such a manner that the various parts of the same retain the same relative position toward each other, and the tapes are not exposed to an undue strain whether the length of the waist-band be increased or decreased, and the proper shape of the skirt is preserved.

To enable others skilled in the art to fully understand and use my invention, I will proceed to describe it.

A is the waist-band, from which the bustle-rings B B' and the hoops C are suspended by means of tapes D in the ordinary manner. The waist-band A is provided with three (more or less) elastic strips, a a', which are secured to the leather or other material from which the waist-band is made by stitching or in any other desirable manner. The elastic strips are made of shirred india-rubber or other suitable material sufficiently strong to give a firm hold to the waist-band around the

body of the person wearing the same, and at the same time allowing said waist-band to stretch easily and to accommodate itself to the circumference of the body.

The rings B B', which form the bustle of the hoop-skirt, are made of two or more parts, which are connected to each other by sliding clasps b b', allowing said rings to expand or contract at pleasure. The clasps b are in line with the elastic strips a on the sides of the waist-band, and the clasps b' are in line with the elastic strip a' on the back, the tapes D being secured to the waist-band and to the rings on the sides of the elastic strips and clasps, as clearly shown in Fig. 2 of the drawings. If the strips a expand, and the next adjoining ring, B, was not allowed to expand correspondingly, a strain would be exerted on the tapes adjoining said strips, exerting a tendency to tear them off from the wrings or waist-band. This injurious strain would extend in a certain measure to the fastenings of the succeeding tapes and bustle-rings, and, furthermore, the bustle would be thrown out of shape. The same effect would take place if an expansion of the strip a' in the waist-band should take place, and the clasp b' would be made rigid. By combining the self-adjusting waist-band with the sliding clasps of the bustle-rings, the skirt adjusts itself freely to the thickness of the body, the bustle retains its proper shape, and the tapes are never exposed to an excessive strain.

I do not claim as my invention the use of elastic strips in the waist-band of a hoop-skirt, neither do I claim the application of sliding clasps to the hoops; but

What I do claim, and desire to secure by Letters Patent, is—

The employment of the self-adjusting waist-band A, with elastic strips a a', in combination with the bustle-rings B B', provided with sliding elasts b b', arranged in relation to the strip a a' and tapes D, in the manner and for the purpose substantially as shown and described.

CÆSAR NEUMANN.
